UNITED STATES PATENT OFFICE.

HUGH WILLIAMSON KELLY, OF TRENTON, NEW JERSEY, ASSIGNOR OF ONE-HALF TO
AUBREY LOVE, OF RIDGEWOOD, NEW JERSEY.

TRACK-TORPEDO.

1,248,667.

Specification of Letters Patent.

Patented Dec. 4, 1917.

Application filed December 3, 1915. Serial No. 64,869.

To all whom it may concern:

Be it known that I, HUGH WILLIAMSON KELLY, a citizen of the United States, and a resident of Trenton, Mercer county, New Jersey, have invented certain Improvements in Track-Torpedoes, of which the following is a specification.

My invention relates to track torpedoes; and the object of my invention is to provide a torpedo with a simple form of rail attaching means highly efficient in operation, and one that is cheap to manufacture.

One object of my invention is to provide a torpedo with self-contained means whereby it may be held in engagement with the head of a rail; while a further object is to mount the detonating part of a torpedo in a non-metallic rail-engaging element or member. To this end, one feature of my invention consists in providing a torpedo with a so-called "sucker" or vacuum cup, made of rubber or similar material, whereby such torpedo may be held to the rail without the use of the usual metal securing straps. In some instances the "sucker" or vacuum cup may be provided with a tacky or sticky substance whereby its adhesion to the rail will be assisted, and in other instances the tacky or sticky substance may be used alone as the means for securing a torpedo to the head of a rail.

These and other features of my invention are more fully described hereinafter, reference being had to the accompanying drawings, in which:

Figure 1, is a sectional view of a rail-head showing one manner of securing a torpedo thereto within the scope of my invention;

Fig. 2, is a sectional view illustrating a modified form of attaching device;

Fig. 3, is a sectional view illustrating another form of torpedo;

Figs. 4 and 5, are sectional views of other forms of torpedo securing devices;

Fig. 6, is a perspective view of the structure shown in Fig. 5, and

Fig. 7, is a perspective view illustrating another form of torpedo within the scope of my invention.

50 The "sucker" or vacuum which I employ

as the means for securing the torpedo to the head of a rail is preferably made of rubber, although it is obvious that any suitable material may be employed, and it is molded substantially to the shape shown in Fig. 1, 55 wherein, however, the vacuum cup is shown slightly depressed in the position that it will assume when applied to the head of a rail. The vacuum cup, indicated at 1, is preferably provided with a cavity 2 on the upper side which is adapted to receive a body of detonating material 3. This may be in the form of a pressed or shaped cake, preferably with a convex upper surface facilitating crushing engagement by the 60 wheel of an engine or train, or it may be of any other shape so long as the "sucker" or vacuum cup with which it is combined is of a practical type, which means, relatively speaking, that its rail-engaging portion 65 should be substantially annular in outline or contour.

If desired, the detonating material may be loose and confined by a suitable bag, wrapper or other container, as may be desired, 75 and in all instances such detonating material, whether in the form of a shaped cake or contained in a wrapper, should be properly water-proofed. This may be done in any well known manner, as by dipping the torpedo proper into a bath of shellac, paraffin or any other non-hygrosopic coating liquid, or it may be inclosed in a waterproof wrapper.

In the form of "sucker" or vacuum cup 85 illustrated in Fig. 1, a solid diaphragm or partition 4 underlies the detonating material or the torpedo proper, but in some instances this solid wall may be omitted, and in Fig. 2, I have shown a form of structure 90 in which this partition or diaphragm is centrally apertured, as indicated at 5. The contact of the annular flange or wall of the "sucker" with the torpedo body will be substantially air-tight and insure proper operation of the "sucker" or vacuum cup and its adherence to the rail head.

In Fig. 3, I have shown a form of my invention in which the detonating material, whether in the form of a shaped cake or 100

loose, is inclosed in a wrapper 6 of substantially waterproof material, which may be secured together in any suitable manner, and this torpedo "package" may be secured to 5 the "sucker" or vacuum cup by the aid of glue or other adhesive as indicated at 7. In such instance, the vacuum cup preferably has a recessed upper portion to receive the torpedo "package", but in view of the use 10 of the adhesive material, there is no necessity for the flange of the vacuum cup to actually overlie the edge of the torpedo "package".

It will be understood, of course, that it is 15 not essential that the size of the "sucker" or vacuum cup equal that of the torpedo, and in Figs. 4, 5 and 6, I have shown an arrangement in which the "sucker" part is relatively smaller than the torpedo or body of 20 detonating material. In the form or arrangement shown in Fig. 4, a cup-like receptacle 2 is provided for the torpedo, as in the structure illustrated in Fig. 1, while in the form of structure shown in Figs. 5 and 6, 25 I provide an integral strap or band 8 carried by the "sucker" portion, which strap or band encircles the body of the torpedo; such arrangement being more clearly shown in the perspective view, Fig. 6.

30 In some instances, it may be desirable to provide the "sucker" or vacuum cup with some form of sticky or tacky material which will assist in causing adherence to the head of a rail, and I have shown a portion of 35 the surface of the structure of Fig. 4 provided with a sticky or tacky coating 9, which will be of any suitable material relatively non-drying in character. Before being put into use, the sticky or tacky coating on the 40 surface of the vacuum cup should be properly protected by a removable covering.

In Fig. 7, I have shown another form of torpedo, which consists simply of a torpedo body 3^a of detonating material, with or 45 without a covering, one surface of which has been rendered sticky by the application of a suitable adhesive 9^a; the same being protected by a removable cover 10.

The manner of employing a "sucker" or 50 vacuum cup such as I propose for securing a torpedo to the head of a rail is too well known to require explanation, and it will be understood, of course, that it will be advantageous to slightly wet the edges of the 55 vacuum cup or "sucker" before it is applied to the head of a rail.

As may be well understood, the torpedo or body of detonating material may be of any shape desired, since its combination or 60 attachment to a carrier structure with a vacuum cup of the usual circular type is a simple matter.

An important point in connection with the

use of a vacuum cup of rubber or similar suitable material for the purpose of holding 65 a track torpedo to a rail is the fact that upon explosion the holder will be substantially entirely destroyed or, if not actually destroyed, any flying parts are incapable of causing any damage whatever. In the case 70 of a torpedo secured to the head of a rail by an adhesive, of course all of the torpedo would be destroyed in the explosion thereof.

I claim:

1. The combination, in a track torpedo, of 75 a body of detonating material, and a receptacle therefor having a vacuum cup securing portion.

2. The combination, in a track torpedo, of 80 a body of detonating material, and a vacuum cup associated therewith whereby the detonating material may be held in position on the head of a rail.

3. A track torpedo comprising a vacuum cup having a recessed head, and a body of 85 detonating material filling the recess in said head.

4. A track torpedo comprising a receptacle, a body of detonating material fitted 90 within said receptacle, and an annular flange 90 surrounding a recessed portion thereof and forming a vacuum cup whereby the torpedo may be held to the head of a rail.

5. A track torpedo comprising a receptacle of rubber, a body of detonating material fitted within said receptacle, and an annular flange surrounding a recessed portion thereof and forming a vacuum cup whereby the torpedo may be held to the head 95 of a rail.

6. A vacuum cup adapted to receive and support a track torpedo; said vacuum cup being provided with a sticky substance upon the engaging portion thereof.

7. A vacuum cup adapted to receive and support the detonating portion of a track torpedo; said vacuum cup being provided with a sticky substance upon the engaging portion thereof.

8. As a new article of manufacture, a track 110 torpedo comprising a partition or diaphragm having an annular wall or flange which forms with the partition or diaphragm a concavity or recess to provide a vacuum cup whereby such structure may be secured to 115 the head of a rail, and a body of detonating material permanently associated with the vacuum cup structure.

9. As a new article of manufacture, a track 120 torpedo comprising a substantially central partition or diaphragm, annular walls or flanges surrounding said central partition or diaphragm on opposite sides thereof and forming therewith concavities or recesses, one of which provides a vacuum cup 125 whereby such structure may be secured to

the head of a rail, and a body of detonating material secured in the opposite recess.

10. As a new article of manufacture, a body of resilient or flexible material comprising a substantially central partition or diaphragm, annular walls or flanges surrounding said central partition or diaphragm

on opposite sides thereof and forming therewith concavities or recesses, one of which provides a vacuum cup whereby such structure may be secured to the head of a rail, and a body of detonating material secured in the opposite recess. 10

HUGH WILLIAMSON KELLY.
